WHIRLIGIG

Filed Nov. 21, 1927

Fig. 1.

UNITED STATES PATENT OFFICE

STANLEY McCLELLAN, OF HIGHLAND PARK, MICHIGAN

WHIRLIGIG

Application filed November 21, 1927. Serial No. 234,831.

My invention relates to a new and useful improvement in a whirligig in which a plurality of radially extending seat bearing members are rotatably mounted and propelled around a central support by means of a person seated thereon.

I am aware that a number of whirligigs have been produced but the present invention relates to one which is economically manufactured, durable in its structure, easily and quickly operated, easily installed and mounted in position and which occupies a minimum amount of space.

To provide such a device is an object of the present invention.

Another object of the invention is the provision of a structure of this class which may be adapted for use with children of different ages so that the elevation of the seat bearing members from the ground may be readily adjusted with a minimum amount of changes.

Another object of the invention is the provision of a circular track which is formed sectional so that it may be folded into compact form when not in use.

Other objects will appear hereinafter.

The invention consists in the combination and arrangement of parts hereinafter described and claimed.

The invention will be best understood by a reference to the accompanying drawings which form a part of this specification and in which

Fig. 1 is a top plan view of the invention.

Fig. 2 is a sectional view taken on line 2—2 of Fig. 1.

Fig. 3 is an end elevational view illustrating one of the seat bearing members.

Fig. 4 is a fragmentary sectional view taken on line 4—4 of Fig. 1.

The invention comprises a hub 7, projecting outwardly from the lower end of which is a flange 8, to which is secured the angularly turned ends 9 of the supporting legs 10, the opposite ends 11 of said legs being angularly turned to extend parallel to the flange 8. Threaded, or otherwise fixedly secured in the hub 7 and projecting upwardly therefrom is a central standard or post 12. A seat support carrying plate 13 is provided

with a suitable thrust bearing 14 on its end side to engage the upper end of the hub 7 when this seat bearing support is positioned on the post or standard 12.

As shown in Fig. 1, a plurality of tongues 15 project outwardly from the plate 13, these tongues 15 serving as a means for attaching the seat support thereto. It is believed obvious that the number of tongues 15 may be as desired, and in Fig. 1 I have shown four of the tongues 15 with the seat support attached to only one, it being obvious that when operated a seat support would be attached to each of the tongues 15.

The seat support comprises a frame having the side rails 16 and 17 and the end rail 18, these rails being preferably formed from angle iron. The ends of the rails 16 and 17 converge, as shown in Fig. 1, and are attached to one of the tongues 15 by bolting, riveting, or in any other suitable manner. Connecting the converged ends of the side rails 16 and 17 is a brace 19. Attached at one end, centrally, to this brace 19 is a brace 20 which extends outwardly and downwardly and is connected at its angularly turned end 21 to the undersurface of the horizontally disposed portion 22 of the bolster 23 which is connected at its opposite ends to the side rails 16 and 17. A bar 24 serves to connect the rails 16 and 17 at the point of attachment of the bolster 23 thereto. Mounted on the horizontally extending portion 22 of the bolster 23 is a suitable bearing 25 in which is journalled one end of a crank shaft 26, the opposite end being journalled in a bearing 27 mounted on the horizontally disposed portion 28 of a bolster 29 which is secured at its opposite ends to the rails 16 and 17 at their outer ends. Mounted on the cranks of the crank shaft 26 are pedals 30 and 31. Fixedly mounted on the crank shaft is a wheel 32. Mounted on the rails 16 and 17 by suitable brackets 33 and 34 is a seat block 35 on which a seat 36 is mounted. This seat block has been illustrated in the drawings as formed in the image of a horse, but it will be obvious that various forms may be given this seat block. Handholds 37 and 38 are

projected outwardly from one end of the seat block 35.

Resting upon the angularly turned ends 11 of the supporting legs 10 is a channel-shaped bracket comprising the semi-circular sections 39 and 40 which are hingedly connected together at their meeting ends.

Rods 44 connect adjacent seat supporting members to each other and serve as reinforcements so that a relative movement of the seat supporting members is prevented, thus eliminating any twisting or undue movement which might destroy the balance of the structure.

It will be noted that the angularly turned ends 11 form a bed for the bracket, thus assuring a smooth running of the device when the crank shaft 26 is rotated and the seat caused to travel on its support around the central post or standard 12.

It is believed obvious that the device is simple in its structure, while at the same time, it is durable and one which may be easily and quickly moved from place to place.

While I have illustrated and described the preferred form of my invention, I do not wish to limit myself to the precise details of structure shown, but desire to avail myself of such variations and modifications as come within the scope of the appended claims.

Having thus described my invention, what I claim as new and desire to secure by Letters Patent is:

1. A whirligig of the class described, comprising: a hub; a supporting standard secured to and projecting upwardly from said hub; a plurality of legs secured to and projecting downwardly and outwardly from said hub, the outer ends of said legs being angularly turned to lie in a plane at right angles to the axis of said supporting standard; a circular track positioned on said angularly turned ends of said legs; a plate rotatably mounted on said standard; a plurality of seat supports projecting outwardly radially from said plate; a pair of spaced bolsters mounted on each of said supports; bearings on said bolsters; a crank shaft rotatably mounted in said bearings; and a wheel on said crank shaft engaging said track.

2. A whirligig of the class described, comprising: a hub; a supporting standard secured to and projecting upwardly from said hub; a plurality of legs secured to and projecting downwardly and outwardly from said hub, the outer ends of said legs being angularly turned to lie in a plane at right angles to the axis of said supporting standard; a circular track positioned on said angularly turned ends of said legs; a plate rotatably mounted on said standard; a plurality of seat supports projecting outwardly radially from said plate; a pair of spaced

bolsters mounted on each of said supports; bearings on said bolsters; a crank shaft rotatably mounted in said bearings; a wheel on said crank shaft engaging said track; a seat on said seat supporting member; and pedals on said crank shaft accessible to a person occupying said seat for rotating said crank shaft.

3. A whirligig of the class described, comprising: a hub; a standard projecting upwardly from said hub; supporting legs for said hub, the ends of said supporting legs being angularly turned to lie in a plane perpendicular to the axis of said standard; a track engaging said angularly turned ends of said legs; a plate rotatably mounted on said standard; a plurality of outwardly projecting portions on said plate; a seat supporting member secured to and projecting outwardly from each of said outwardly projecting portions; a pair of spaced bolsters depending from said seat supporting member; a brace connecting the innermost of said bolsters to said seat supporting member, adjacent said outwardly projecting portion to which attached; a shaft rotatably mounted and extending between said bolsters; and a wheel on said shaft and engaging said track.

In testimony whereof I have signed the foregoing specification.

STANLEY McCLELLAN.
